(57) **CLAIM**

The ornamental design for a ladder stabilizer, as shown and described.

DESCRIPTION

FIG. 1 is a front right perspective view of a ladder stabilizer according to a first preferred embodiment of the present invention.

FIG. 2 is a rear left perspective view of the ladder stabilizer shown in FIG. 1.

FIG. 3 is a front view thereof.

FIG. 4 is a left side view, the right side being a mirror image thereof.

FIG. 5 is a rear view thereof.

FIG. 6 is a top view thereof.

FIG. 7 is a bottom view thereof.

FIG. 8 is a front right perspective view of a ladder stabilizer according to a second embodiment of the claimed design shown in FIG. 1.

FIG. 9 is a top view thereof.

FIG. 10 is a front perspective view of the ladder stabilizer shown in FIGS. 8-9, with the ladder stabilizer being used in conjunction with a second, broken line ladder stabilizer installed onto a ladder shown in broken lines.

FIG. 11 is a front right perspective view of a ladder stabilizer according to a third embodiment of the claimed design shown in FIG. 1.

FIG. 12 is a rear left perspective view of the ladder stabilizer shown in FIG. 11.

FIG. 13 is a front view thereof.

FIG. 14 is a left side view, the right side being a mirror image thereof.

FIG. 15 is a rear view thereof.

FIG. 16 is a top view thereof; and,

FIG. 17 is a bottom view thereof.

The broken lines of FIGS. 1-9 represent structure or features that form no part of the claimed design. The broken lines of FIG. 10 represent environmental structure which forms no part of the claimed design.

The appearance of any portion of the ladder stabilizer between the break lines shown in FIGS. 1-7 forms no part of the claimed design.
